UNITED STATES PATENT OFFICE

2,602,930

GLOVE

Willoughby W. Tayler, New York, N.Y.

Application April 1, 1949, Serial No. 84,797

2 Claims. (Cl. 2-162)

1

This invention relates to gloves having an opening extending from one edge to an intermediate portion thereof and to a slide fastener for closing the opening.

An object of this invention is to provide a glove which may be worn by men, women and children and generally made of leather, and to provide a metallic seam at the front or at the rear portion of the glove to facilitate the insertion of the hand of the user into the glove.

Another object of this invention is to provide a modified glove having a slide fastener and having a lining with an opening in alignment with the slide fastener opening, and to provide means whereby movement of the slider in the upright direction will cause the lining opening to be closed simultaneously with the opening of the slide fastener.

Another object of this invention is to provide cords made of plastic material or other generally non-compressible material, the cords being secured to the edges defining the opening in the lining and the slider having clip members engageable with the cords to cause movement of the cords toward each other when the slider is raised.

Another object of this invention is to provide gussets in the lining fabric adjacent the upper ends of the cords, the gusset portions of the lining preferably having a degree of rigidity or stiffness imparted thereto by impregnating a chemical therein, whereby when the slider is lowered the resilient gussets will move the cord portions of the lining to points where the lining is fixed to the glove fabric by stitching.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, in which:

Figure 1 is a front view of the glove having an opening closed by a slide fastener.

Figure 2 is a central cross-sectional inside view of the glove shown in Figure 1, modified to include a lining and a rear slide fastener.

Figure 3 is a top view of the lined glove shown in Figure 2.

In the illustrated embodiment of the invention, the numeral 10 indicates a glove of the type worn by men, women and children and generally made of leather.

The glove 10 has an elongated vertical opening 11 extending from the top edge 12 to a point 13 substantially intermediate the glove.

The opening 11 is closed by a slide fastener 14

60

comprising cooperating stringers or fabric tapes 15 having fastening means or a plurality of pairs of opposed locking members which are manipulated to open or closed position by means of the slider 16 in a manner which is well understood in the glove making art.

The tapes 15 are attached to the sides defining the opening 11 by stitching 17 extending the entire length of the opening.

10 By means of the slide fastener 14, the metal seam along the opening 11 may be opened quickly and conveniently for ease of insertion of the hand of the user into the glove.

Figure 2 is a central cross-sectional view of a modified form 10' of the glove shown in Figure 1. The form 10' comprises an elongated vertical opening 11' similar to the opening 11.

The opening 11' is closed by a slide fastener 14' comprising cooperating stringers or fabric tapes 15' which are manipulated to open or closed position by the slider 16' similar to that shown in Figure 1.

The modified form 10' has a lining fabric 20 having an opening 21 and a reinforcing cord 22 stitched to both edge portions defining the opening 21 and forming outlying edgings, the edgings being considerably thicker than the lining fabric.

For the above purpose, the cord 22 is substantially non-compressible. The cord is secured to the lining fabric by cementing to the lining. The cord may also be secured to the lining by zig-zag stitching, the stitching piercing the lining fabric and the cord successively in two different and slightly spaced longitudinal lines.

35 The lining has expanding gussets 25 adjacent the upper ends of the cords 22, the lining having stitching 26 terminating at the gussets.

It is to be noted that the lining portions including the cords 22 and the gussets 25 up to the stitching 26 is free to move to and from the middle of the opening 21. It is also to be noted that the gusset portions of the lining fabric 20 may be stiffened with a suitable chemical to provide resiliency or a bellows effect whereby these freely movable lining portions will inherently move away from the central portion of the opening 14 when the slider 16' is in the lowered position as shown in Figure 2.

It is also to be noted that the slider 16' has clip means of curved cross-section and of a size adapted to grip the cords 22.

When the slider 16' is moved upwardly to close the slide fastener 14', the clip means 27 bring the cords 22 toward each other and this causes the lining opening 21 to close simultaneously with the closing of the opening 11' in the body of the glove.

In accordance with the patent statutes I have described and illustrated the preferred embodiment of my invention, but it will be understood

that various changes and modifications can be made therein without departing from the spirit of the invention as defined by the appended claims.

I claim:

1. A glove comprising in combination an integral hand encircling member and a wrist portion, the latter having an opening extending from the top edge thereof to the top of the hand member, a slide fastener for detachably closing said opening comprising two fabric tapes secured to the glove material along the edges of said opening, interlocking fastening means on the adjacent edges of said tapes, a slider on said fastening means for opening and closing said slide fastener, said glove having a lining with gussets on opposite sides of said wrist and body opening, and an opening defined by side edges considerably thicker than said lining, said openings being coextensive, said slider having means in engagement with said thickened edges of said lining, whereby when said slider is moved to close said wrist and body opening, said lining opening is simultaneously closed.

2. A glove comprising in combination an integral hand encircling body and a wrist portion, the latter having a linear opening extending from the top edge thereof to the top of the hand body, a slide fastener for detachably closing said opening comprising two fabric tapes se-

cured to the glove material along the edges of said linear opening, interlocking fastening means on the adjacent edges of said tapes, a slider on said fastening means for opening and closing said slide fastener, said glove having a lining with gussets on opposite sides of said wrist and body opening, and a lining opening defined by side edges considerably thicker than said lining, said openings being coextensive, said slider having means in engagement with said thickened edges of said lining, whereby when said slider is moved to close said wrist and body opening, said lining opening is simultaneously closed.
